UNITED STATES PATENT OFFICE.

FREDERICK MESINGER, OF NEW YORK, N. Y.

SADDLE FOR MOTOR-CYCLES.

1,133,389.

Specification of Letters Patent. Patented Mar. 30, 1915.

Application filed December 12, 1914. Serial No. 876,787.

To all whom it may concern:

Be it known that I, FREDERICK MESINGER, a citizen of the United States, and a resident of New York city, in the county of Bronx 5 and State of New York, have invented certain new and useful Improvements in Saddles for Motor-Cycles, of which the following is a specification.

This invention relates to a saddle for motor cycles, and more particularly to novel 10 and efficient means for effecting a ready compression and recovery of the back springs, so that friction and noise are avoided, side swaying and bottoming prevented, 15 and an easy riding insured.

In the accompanying drawing: Figure 1 is a side elevation partly in section of a saddle embodying my invention; Fig. 2 a rear view and Fig. 3 a longitudinal section 20 through one of the back springs.

The frame constituting the relatively fixed portion of the saddle comprises a pair of longitudinally extending members 1 which are adapted to be mounted upon the saddle 25 post (not shown) by means of a suitable clasp 2. To the rear ends of members 1, there is bolted at 3, a transverse yoke 4, forming part of the frame, and provided with a pair of laterally extending arms 5. 30 A brace 6 secured to yoke 4 at 7 and extending underneath the main body of the yoke serves to reinforce the latter. Arms 5, are perforated, and through these perforations 35 pass loosely, the lower ends, of a pair of upright rods 8, which are pivotally suspended from the cantle 9. As shown, the latter carries a pair of clevises 10, that loosely embrace eyes 11 formed on upper ends of rods 8. The lower portion of each 40 rod 8, is loosely encompassed by a tubular guide sleeve 12, that rests upon arm 5. Sleeve 12 is provided with an upper bead 13, and a lower bead 14, containing leather packing rings 15, 16 that are adapted to 45 engage rod 8. Rod 8 extends axially through a back compression spring 17, which is coiled around the rod, and also around the sleeve, the convolutes of said spring increasing in diameter from the top

as shown. The uppermost convolute 18 of 50 spring 17, engages eye 11 of rod 8, which thus constitutes a head or abutment. The lowermost convolute 19 of the spring rests upon arm 5 and is contracted to snugly embrace sleeve 12 under the lower bead 14. 55 A nut 20 mounted on the lower threaded end of rod 8 and adapted to engage the lower side of arm 5, prevents any accidental disengagement between rod and frame.

When the cycle encounters an uneven- 60 ness on the road, the pressure on the saddle top will cause a descent of the rods 8 through arms 5, and a consequent compres- 65 sion of springs 17, while when the obstruc- 70 tion is cleared, the springs will, on rebound- 75 ing, raise the top together with the rods. In this way there is imparted to the rods, a reciprocative or piston-like movement during which movement, they will be so guided by sleeves 12, that any side swaying 80 or bottoming is prevented. So also owing to the packing interposed between rods and sleeves, any friction of metal against metal is prevented, thus insuring a noiseless and free action of the springs and coöperating 85 parts. Finally the sleeves besides constituting guides for the rods assume the additional function of properly centering the springs at their lower ends.

I claim:

1. A saddle provided with a saddle top, a rod depending therefrom, a relatively fixed frame adapted to loosely engage the lower end of the rod, a tubular sleeve encompassing the rod and supported upon the 85 frame, and a coiled compression spring encircling the rod and sleeve.

2. A saddle provided with a saddle top, a rod depending therefrom, a relatively fixed frame adapted to loosely engage the lower 90 end of the rod, a tubular sleeve encompassing the rod and supported upon the frame, said sleeve having a pair of beads, a pair of packings within the beads, and a compression spring encircling the rod and 95 sleeve.

3. A saddle provided with a saddle top, a rod depending therefrom, a relatively fixed

frame adapted to loosely engage the lower end of the rod, a tubular sleeve encompassing the rod and supported upon the frame, said sleeve having an upper bead and a lower bead, packings within said beads, and a compression spring encircling the rod and sleeve, said compression spring

being provided with a lower contracted convolute that engages the sleeve below the lower bead.

FREDERICK MESINGER.
